ATTORNEY

UNITED STATES PATENT OFFICE.

ARTHUR YANCEY, OF NEW ORLEANS, LOUISIANA.

TUMBLER CAP AND CLOSURE.

Application filed June 12, 1925. Serial No. 36,739.

The invention relates to preserving caps and closures.

The main object of the invention is to provide a practical glass tumbler-cap and closure.

This and other objects are attained by the invention, one form of which is herein described and illustrated by the accompanying drawings.

10 Fig. 1 is a cross section on the line 1—1, Figure 3, of the tumbler, cover and fastener.

Fig. 2 is a cross section of the same on the line 2—2, Figure 3.

15 Fig. 3 is a plan view of the tumbler, cover and fastener.

Figs. 4, 5, 6 and 7 are detail views of fastener parts which are fully described herein.

20 The tumbler 3, a receptacle usually in the form of the frustum of a cone, and the cap 4 are preferably made of glass. The upper part of the cap is provided with a border 5 which surrounds and forms a concavity 6 adapted to contain operating parts of the fastener. The lower part of the cap

25 is provided with a wedge-shaped projection 7 which has a rib or part thereon 8 adapted to support and hold a gasket 9. The form of the support for the gasket is substantially symmetrical to the interior part of the

30 mouth of the tumbler, that is to say to the rim of the tumbler 10 and to the surface contiguous thereto 11.

The fastener may conveniently comprise the strap 12, a flexible connecting band 13

35 and the eccentric lever 14. The latter is pivoted to the aforesaid strap at 15 and comprises lips 16 and 17 conveniently formed by bending the metal of which it is made

(see Figure 4) on the lines 18 and 19, and

40 so proportioned that the distance 20 (see Fig. 1) exceeds the distance 21 by the desired movement of the cap to the tumbler when sealing. The pivoted position of the lever aforesaid is maintained by the binding

45 plate 22 (see Fig. 5); the division 23 being bent or stamped to fit the strap. The edges 24 and 25 are turned under the forward

edges of the lever 26 and 27 (see Fig. 4), and the edge 28 is bent around the rear edge

50 29 of the lever. The metal of which the connecting band aforesaid is made (see Fig. 7) may be bent on the line 30 and the side parts may be curved as at 31 to fit the surface of

the tumbler.

55 In operation, the cap is put on the tumbler with the pivoted lever placed in the con-

cavity aforesaid, first with the lever parallel to the axis of the tumbler; then, after the strap has been swung over the edge 32 of the tumbler and the compensating flexible band 60 is advanced to the position shown in Fig. 1, reasonably taut, the lever is turned down transversely to the axis of the tumbler, as shown, and the cover is air tight.

It will of course be observed that the distance 33—32 (see Fig. 1) is greater than the distance 33—34, but on the other hand the width of the bottom of the tumbler increases from 32 to maximum at 34. These facts together with the flexibility of the connecting band, which adjusts to the circular bottom of the tumbler in passing, produce the desired taut condition of the strap when swung to the position shown in Fig. 1.

The downward pressure of the cap and gasket on the rim of the tumbler, owing to the construction and operation described, resolves partly into lateral pressure on the interior surface contiguous to the rim of the tumbler.

This may be practically and visibly illustrated and observed in operating the constructions shown in Figs. 1, 2, and 3.

Through the clear glass cap and tumbler the gasket will be seen to be jammed outwardly or laterally against the interior surface of the tumbler as well as downward upon the rim.

Thus slight variations in diameter as well as in rim are compensated, and the seal is 90 made over the interior surface as well as over the rim of the tumbler.

Expansion of the gasket under internal pressure in process cannot injure the seal.

Gaskets can easily be cut from a tube of correct size and thickness without loss of material. The resulting gaskets will be like ordinary rubber bands, that is to say like bands with edges of equal length as contradistinguished from circular gaskets molded 95 or cut from flat sheets. Material $\frac{1}{2}$ of an inch thick and $\frac{1}{8}$ of an inch wide will give satisfactory results.

Owing to the form of support described, gaskets may be used in a stretched condition as well as in exact fit; therefore the gaskets may be sterilized and used more than once.

When the cap and tumbler are closed, the fastener does not interfere with packing, shipping or storing.

For the purpose of disclosure and illustration, I have shown a simple and elemental

form of the invention, which obviously may be embodied in other forms.

I claim and desire to protect by Letters Patent combinations including all of the same elements, or equivalent elements, included in the following claim:

A cap for receptacles comprising a projection conforming in shape with the interior of the opening of the receptacle to be covered and capable of fitting therein, a rib around said projection near one end thereof,

a flange parallel to said rib of greater periphery near the other end thereof for resting over the edges of the opening of the receptacle, a continuous arcuate surface between the rib and the interior edge of the flange connecting the former with the latter, and a ribbon like gasket extending from said rib covering said arcuate surface and extending as a flat covering upon the flange. 15

ARTHUR YANCEY.
